A. H. KERNGOOD,
BUCKLE,
APPLICATION FILED DEC. 31, 1918.

Patented Apr. 8, 1919.

Fig. 1.

^{Inventor}
Allen Herman Kerngood
By Henry J. Brewington,

^{Attorney}

UNITED STATES PATENT OFFICE.

ALLEN HERMAN KERNGOOD, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

BUCKLE.

1,299,734.

Specification of Letters Patent.

Patented Apr. 8, 1919.

Application filed December 31, 1918. Serial No. 269,041.

To all whom it may concern:

Be it known that I, ALLEN HERMAN KERNGOOD, a citizen of the United States, residing at Baltimore city, State of Maryland, have invented certain new and useful Improvements in Buckles, of which the following is a specification.

This invention relates to buckles for securing the ends of straps and the like, and the invention has for its object to provide a very simple and efficient buckle which is entirely in one piece and therefore easily and cheaply manufactured.

The object stated is attained by means of a novel combination and arrangement of parts to be hereinafter described and claimed, and in order that the same may be better understood, reference is had to the accompanying drawing, forming a part of this specification.

In the drawing,

Figure 1 is a plan view of the buckle;

Fig. 2 is a central longitudinal section thereof;

Fig. 3 is a plan view of the blank out of which the buckle is fashioned, and

Fig. 4 is a perspective view of the buckle.

Referring specifically to the drawing the buckle which is the subject matter of the present application for patent is in the form of a frame composed of parallel, laterally spaced side members 5 connected at their ends by cross bars 6 and 7, respectively, and intermediate their ends by a cross bar 8.

These cross bars are flat and the side members are also flat.

The end cross bar 6 has a downturned outer edge 9 forming a depending flange, from which latter project spurs 10 which have a slight curve so that their extremities lie beneath the cross bar and are spaced therefrom.

The side members 5 depend from the cross bars 6, 7 and 8, and they are located on the same side thereof as the spurs 10.

The cross bar 8 has a slight downward bend, as shown in Fig. 4 so that it is offset downwardly with respect to the end cross bars 6 and 7.

In use, one end of the strap is looped around the intermediate cross bar 8 as shown at 11 in Fig. 2, and allowed to project from

that end of the buckle having the cross bar 7. The other end 12 of the strap enters the buckle from the opposite end having the cross bar 6, beneath which latter it passes so that the spurs 10 may be stuck through the strap end as shown in Fig. 2. The strap end 12 is also passed over the top of the cross bar 8 and beneath the end cross bar 7, so that its extremity now projects from that end of the buckle which is entered by the looped end 11 of the strap, the latter now lying beneath the strap end 12. Both strap ends seat between the depending side members 5 of the buckle. By passing the strap end 12 over the intermediate cross bar 8, this portion is held elevated above the extremities of the spurs 10, and is thus prevented from accidentally slipping off the latter. Tension on either or both ends of the strap holds the end 12 securely empaled on the spurs 10.

As shown in Fig. 3 the device is made out of a single piece of sheet metal or other suitable material which is formed by punching or otherwise with two transverse slots 13 to define the cross bars 6, 7 and 8. Opposite side portions of the blank are bent down on the dotted lines 14 to form the side members 5, and a narrow projecting end portion of the blank carrying the spurs is bent down on the dotted line 15 to form the flange 9 and to properly position the spurs. The device is therefore easily and cheaply produced.

I claim:

A buckle comprising side bars, end cross bars and an intermediate cross bar connecting the side bars, the side bars depending from the cross bars, one of the end cross bars having a depending flange carrying inwardly directed spurs, and the other end bar being flat and lying wholly inside the side bars, the intermediate cross bar being positioned below the plane of the end cross bars.

In testimony whereof I affix my signature in the presence of two witnesses.

ALLEN HERMAN KERNGOOD.

Witnesses:

HOWARD D. ADAMS,
E. WALTON BREWINGTON.
